UNITED STATES PATENT OFFICE.

DONALD H. REEVES, OF DETROIT, MICHIGAN, ASSIGNOR, BY MESNE ASSIGNMENTS, TO STROMBERG MOTOR DEVICES COMPANY, OF CHICAGO, ILLINOIS, A CORPORATION OF ILLINOIS.

HYDROCARBON MOTOR.

Application filed November 17, 1917. Serial No. 202,677.

To all whom it may concern:

Be it known that I, DONALD H. REEVES, a citizen of the United States, and resident of Detroit, Wayne County, State of Michigan, have invented certain new and useful improvements in Hydrocarbon Motors, of which the following is a specification.

This invention relates to hydrocarbon motors and particularly to means for supplying clean air thereto.

In the use of motor vehicles, particularly for truck and tractor purposes, some difficulty is experienced in connection with the motor because of dust laden air being taken in through the carbureter. It is one of the objects of the present invention to separate the dust from the air which is being drawn into the carbureter.

Another object of the invention is to provide a tortuous passage for the air drawn into the carbureter of a hydrocarbon motor together with means for catching and removing from the air the dust particles drawn in with it.

Another object of the invention is to provide a tortuous passage for the air entering the carbureter of a hydrocarbon motor together with means for withdrawing dust from said chamber by ejector action.

Other objects of the invention will appear from the following description taken in connection with the drawings which form a part of this specification, and in which:

Fig. 1 is a plan view of a hydrocarbon motor embodying the invention;

Fig. 2 is a side elevation of the motor illustrated in Fig. 1;

Fig. 3 is an enlarged sectional view of the dust separating device shown in connection with the motor illustrated in Figs. 1 and 2;

Fig. 4 is an end view of the dust collector shown in Figure 3 and disconnected from the exhaust pipe sleeve;

Fig. 5 is a view similar to Fig. 3, illustrating another form of dust collector.

Referring to the drawings, 10 represents a hydrocarbon motor having a carbureter 11 of any desired construction, and a fan 12 driven through a belt 13 from a moving shaft of the motor. It will be understood that the carbureter 11 has an air intake opening 14 which in the present instance is connected to a pipe 15 which leads around

the front part of the motor to the opposite side thereof, as will be hereinafter more fully described, and the fan 12 is designed to operate immediately at the rear of a radiator (not shown in the drawings) and thereby produces a current of air passing rearwardly over the motor.

An exhaust pipe 16 is shown in the drawings as arranged at the side of the motor opposite the carbureter side and a sleeve 17 partly surrounding and separated somewhat from the exhaust pipe has its interior connected with a tube 18 which leads to a chamber 19 connected to the pipe 15, above referred to. By this arrangement the air supplied to the intake 14 of the carbureter through the sleeve 17, tube 18, chamber 19 and pipe 15 is warmed somewhat by passing over a part of the heated exhaust pipe 16.

The chamber 19 is shown in longitudinal section in Fig. 3 and it will be seen that it is provided with an inlet opening 20 at one end and an outlet opening 21 at the other end, both of which openings are in the upper part of the chamber. The inlet opening is connected to the tube 18 and the outlet opening to the pipe 15, and the passage 22 through the chamber between these openings is a tortuous one, being interrupted by baffles 23 which extend somewhat into the curved parts 24 of the passage.

The lower part of the chamber 19 has a secondary inlet opening 25 at the opposite end of the chamber from the inlet opening 20 and beneath the outlet opening 21, and there is a secondary outlet opening 26 at the opposite end of the chamber from the outlet opening 21 and beneath the inlet opening 20. Between these openings 25 and 26 there is formed a substantially direct passage 27, which passage is connected at several points with the tortuous passage 22 by transverse passages 28. These passages 28 preferably open into the passage 22 adjacent the respective baffles 23, and they are shown as curved and as making an acute angle with the passage 27 at their junction with said latter passage.

The inlet opening 25 is connected by a pipe 29 with a funnel-shaped device 30 opening forwardly and arranged immediately at the rear of the fan 12, above referred to, and the outlet opening 26 is connected to a pipe

31 which leads to a point beneath the motor where it is open to the atmosphere underneath the vehicle.

By this arrangement of passages and piping it will be seen that when the motor is running and the fan 12 is therefore in operation a current of air is caused to pass into the funnel 30 through the pipe 29 and opening 25 into and through the passage 27 and out of the chamber through the outlet opening 26 and pipe 31. There is practically nothing to retard this current of air because of the substantially direct arrangement of the passage 27. It will also be seen that by the operation of the motor air will be drawn into the carbureter through the pipe 15, chamber 19 and sleeve 17. As this air passes through the tortuous passage 22 of the chamber the particles of dust carried by it will strike against the various baffles 23 and be directed downwardly into the passages 28. The greater part of the air will of course be carried on through the passage 22 to the outlet 21 and pipe 15, but a small portion of it with the greater portion of the dust will flow into the passages 28 and by the ejector action of the current of air passing through the passage 27 will be drawn into the latter passage and carried off through the opening 26 and pipe 31. Thus the air passing to the pipe 15 and consequently to the carbureter 11 will be freed of part or all of the dust which was combined with it as it entered the sleeve 17.

In Fig. 5 the pipe 15, exhaust pipe 16, and sleeve 17 are the same as in Fig. 3, but the chamber 19^a, while it has a tortuous passage 22, with inlet and outlet openings 20 and 21 respectively, as well as baffles 23, yet it is formed with a somewhat different dust collecting lower portion. In this form of the invention the passages 28^a which are formed adjacent the baffles 23 open downwardly into a catch-basin 27^a which contains a quantity of oil or other liquid, as shown. The basin 27^a is also formed with partitions 28^b which extend downwardly from the respective baffles 23. By this arrangement it will be understood that the air entering the inlet opening 20 impinges against the baffles 23 which causes the greater part of the dust carried by the air to be deflected downward on the surface of the oil in the several compartments of the basin 27^a, this operation taking place at each one of the turns in the tortuous passage 22. As the air emerges through the outlet opening 21 and through

the pipe 15 it has had the greater part or all of the dust separated from it.

It will be understood further that the 60 basin 27^a is detachable from the other part of the chamber, as by removing screws 27^b so that the interior of the basin may be cleaned and oil renewed from time to time.

It will be understood further that my invention is not limited to the details of construction shown and other forms may be used without departing from the spirit or scope of the invention.

Having thus described my invention, what 70 I claim and desire to secure by Letters Patent is:—

1. In a hydrocarbon motor, in combination, a means providing an air intake for a carbureter, an air chamber connected to said intake, a fan driven by the motor, a conduit leading from a point adjacent said fan to said chamber, and baffles in said chamber so arranged as to separate the dust from the air passing to the carbureter intake. 75

2. In a hydrocarbon motor, in combination, a means providing an air intake for a carbureter, an air chamber connected to said intake, a fan driven by the motor, a conduit leading from a point adjacent said fan to said chamber, and curved baffles arranged crosswise in said chamber to deflect dust from the incoming air downwardly and have it carried away by the air from said conduit. 85

3. In combination, a casing, walls in said casing defining passageways, said passageways including two generally parallel passageways extending through said casing, one passageway comprising a plurality of convolutions adapted to separate out material of greater specific gravity than the stream, and a plurality of cross passages between the parallel passages leaving the convoluted passage at the point where material is thrown out, said remaining parallel passage being substantially free of convolutions, but constricted where it joins the cross passages to exert an ejector action thereon. 95

4. In combination, a casing, and walls in said casing defining passages therein including a tortuous passage adapted to separate material by dynamical reaction, cross passages positioned to receive material separated, and a single discharge passage arranged to have an ejector action on all said cross passages. 105

In testimony whereof I affix my signature.

DONALD H. REEVES.
